[57] CLAIM

The ornamental design for a cigar clip for golf, as shown and described.

DESCRIPTION

FIG. 1 is a front perspective view of the cigar clip for golf showing our new design with the phantom lines depicting solely environmental structure and forming no part of the claim design;

FIG. 2 is an enlarged front perspective view thereof;

FIG. 3 is a rear perspective view thereof;

FIG. 4 is a front elevational view thereof;

FIG. 5 is a right side elevational view thereof with the opposite side being a mirror image; and,

FIG. 6 is a rear elevational view thereof.
